STEAM GENERATOR

William Ross Irwin, Springfield, Ill., assignor to
Springfield Boiler Company, Springfield, Ill., a
corporation of Illinois

Application October 29, 1934, Serial No. 750,415

5 Claims. (Cl. 122—297)

This invention relates to tubulous boilers and furnaces therefor and is particularly directed to boilers of large size and generating capacity.

The principal object of the invention is to provide an improved steam generator which will be particularly simple in construction and durable and efficient in operation.

Other objects of the invention are to provide a boiler having a novel form of slag screen and water wall; to provide a boiler of this type in which some of the tubes of the lower bank are bent out of their normal position to provide greater clearance between the lower tubes and also to provide a water wall for the furnace; to provide a water wall for one of the walls of the furnace which is formed of tubes connected with the header of the main bank; to provide improved cooling means for the lower portion of the furnace or walls adjacent to the stoker; and to provide such other novel features of construction and such advantages in use as will be described more fully hereinafter.

In the accompanying drawings illustrating this invention,

25 Figure 1 is a vertical longitudinal section taken on the line 1—1 of Figure 4 and showing a modified form of construction;

30 Figure 2 is a perspective detail of the lower end of one of the headers showing the pipes connected therewith;

Figure 3 is a cross section taken on the line 3—3 of Figure 1;

Figure 4 is a cross section taken on the line 4—4 of Figure 1; and

35 Figure 5 is a sectional plan view taken on the line 5—5 of Figure 1.

In these drawings some of the parts are shown diagrammatically and other parts and attachments common to such apparatus are omitted for convenience in illustration, it being the intention however to provide sufficient information so that one skilled in the art may produce a complete operative steam generator embodying my improved or novel features.

45 In the form of the invention shown in Figures 1 to 5, the boiler has a front header 32, rear header 33 and main bank of tubes 34. The header 32 is connected by circulating tubes 35 with the drum 36 which is connected by supply tubes 37 with

50 the rear header 33.

In the present instance the furnace 38 is shown as being of the type or shape commonly used with chain grate stokers such as indicated at 39. The front of the furnace is provided with a water wall 40. This wall is formed by bending down each

alternate tube in the lower row of the main bank of tubes.

These tubes are preferably bent adjacent to the front header 32 and are so formed as to provide the type of wall and front arch as may be required for the particular type of stoker. The lower portions 41 of these tubes are bent outwardly and connected with a header 42. This water wall may be backed up by a wall 43 formed of any material suitable for this purpose. The lateral spacing of the portions of the tubes 41 forming the front arch is such that T-tile as shown in Figure 3 may be inserted between the tubes and will be supported solely thereby. Such tile forms an ignition arch which is essential or 15 desirable for the front portion of the furnace.

The alternate lower tubes 44 of the lower bank extend across the top of the furnace and are bent downwardly at the rear of the furnace to form a rear water wall 45. The lower ends 46 of these tubes are bent outwardly and are connected with the header 47. This rear water wall may also be backed up with a wall 48 of any suitable material which is arranged to seal with the lower end of the baffle 49. The portions of the rear arch tubes 20 are also spaced as indicated for supporting T-tile 25 in the same way as the front arch, such tile thus providing the necessary rear arch.

The tubes of the main bank may be arranged in any desired manner but as indicated particularly in Figure 2, are arranged in groups of four. The tubes which would ordinarily appear immediately above the tubes 49 are omitted, thus providing an additional space between the tubes of the second row in the second lowermost row 30 of the bank of tubes. This provides a slag screen of two tubes height as will readily be seen from Figures 2 and 4. This screen arrangement taken in connection with the front and rear water walls 35 of the furnace will be sufficient for operation of 40 boilers of this type at moderately high ratings.

The header 33 is connected by nipples 50 with a header 51 which in turn is connected by means of pipe 52 with the headers 47.

In order to prevent overheating and burning 45 out of the refractory side walls 53 of the furnace along the top of the chain grate stoker 39, I provide cooling pipes commonly known as a clinker chill for each side of the furnace. The pipes 54 and 55 at the respective sides of the 50 furnace are arranged immediately above the ledge plates 56 of the stoker. The pipes 54 are connected at the front with a short vertical header 57 and at the rear with a similar header 58. The header 57 is connected by means of a pipe 55

59 with the header 42. The header 58 is connected by means of a pipe 60 with the header 51. The pipes 55 are connected at the front with a short vertical header 61 and at the rear with a similar header 62. The header 61 is connected with the header 42 by means of a pipe 63 and the header 62 is connected with the header 51 by means of a pipe 64.

When the generator is in operation, water from 10 the drum 36 passes down through tubes 37 to the header 33 and a portion thereof returns to the drum through the main bank of tubes 34 in the usual manner. A portion of the water passes downwardly through pipes 52 to the header 47 15 and thence through the tubes of the rear water wall 45 to the header 32. Another portion of the water passes downwardly through the end tubes 60 and 64 to the rear headers 58 and 62 and then through the clinker chill pipes 54 and 55 to the 20 headers 57 and 61 and then through pipes 59 and 63 to the header 42, thus supplying this header with water for the front water wall 40 through which the water passes up to the header 32.

25 On account of connecting the clinker chill or side wall cooling tubes with the front wall 40, positive circulation through the horizontally positioned clinker chill is assured due to its series connection with vertical tubes positioned within 30 the furnace, thus more effectively protecting the sides of the furnace. While I have shown two tubes on either side of the furnace for the clinker chill it will of course be evident that any desired number of these tubes may be utilized for this 35 purpose.

It will be understood that the generator is provided with the necessary supports for the boiler and other features commonly utilized in making a complete operative apparatus but which form 40 no part of the present invention and therefore description of the same does not appear necessary. While my improvements have been illustrated in connection with boilers of the sectional header type it will also be noted that it is also 45 applicable to any other type such as boilers with box headers and either of the cross or long drum type.

It will also be noted that my invention may be subject to various changes or modifications in 50 order to adapt the same to such different types or forms of boilers and therefore I do not wish to be limited to the particular apparatus herein shown and described except as set forth in the following claims, in which I claim:

55 1. In a steam generator, the combination of a boiler having inclined tubes, upper and lower headers for said tubes, a combustion chamber below the tubes, a stoker for supplying fuel to the combustion chamber, a water wall formed of 60 tubes connected with an upper header and extending downwardly along the front of the furnace, a header connected with said tubes, horizontal tubes positioned on either side of the stoker along the adjacent portions of the walls, 65 headers for said tubes, pipes connecting the rear headers of the tubes with the lower header of the boiler, and pipes connecting the front headers of the tubes with the header connected with the water wall tubes.

70 2. In a steam generator, the combination of a boiler having horizontally inclined tubes, front and rear headers connected with said tubes, a

drum, pipes connecting the headers with the drum, a furnace below the tubes, a chain grate stoker for supplying fuel to the furnace, a water wall for one of the walls of the furnace comprising tubes connected with one of said headers, a header connected with the opposite end of the tubes of the water wall, one or more tubes extending longitudinally of the furnace at either side thereof adjacent to the upper surface of the stoker, pipes connecting the rear ends of said last named tubes with the rear header of the boiler, and pipes connecting the front ends of said tubes with the header of the water wall whereby said last named tubes are in flow series with the tubes 10 of the water wall.

3. A steam generator including a boiler having a main bank of horizontally inclined tubes, upper and lower headers connected with said tubes, a combustion chamber below the tubes, a series of tubes connected with the lower portion of the upper header and extending downwardly along the front of the combustion chamber, a conduit connecting the lower ends of said tubes of the last named series, pipes connecting said conduit with the lower header of the boiler, clinker chill tubes positioned on either side of the lower portion of the combustion chamber, rear headers for the respective tubes on either side of the chamber, pipes connecting said 20 headers with the lower header of the boiler, headers for the front ends of the clinker chill tubes, and pipes connecting the last named headers with the conduit of the first named series 25 of tubes.

4. In a steam generator, the combination of a boiler having inclined tubes connected with front and rear headers, alternate tubes of the lowermost row connected with the front header being extended downwardly and forming a front water wall and water cooled arch for the furnace, and other alternate tubes of the lowermost row extending backwardly in normal position along the main bank and then downwardly forming a rear water wall and water cooled arch for the furnace, 50 all of said front and rear water wall and arch tubes being spaced a greater distance apart than those of the main bank of the boiler so as to permit T-tile being inserted between the tubes, and T-tile inserted between said tubes throughout the 55 arch portions thereof to form ignition arches at the front and back of the furnace, said T-tile being supported solely by the tubes.

5. In a steam generator, the combination of a boiler having front and rear headers with inclined tubes connecting the same, alternate tubes of the lowermost row connected with the front header extending downwardly and then forwardly to form a front water wall and water cooled arch, and other alternate tubes of the lowermost 65 row extending backwardly in substantially normal position along the main bank and then downwardly and rearwardly to form a rear water wall and a rear water cooled arch, means for supplying water from the boiler to said water 70 walls, and refractory material supported by said arch portions to form ignition arches.

WILLIAM ROSS IRWIN.
